UNITED STATES PATENT OFFICE.

THOMAS MORTON, OF NEW YORK, N. Y.

RIVETING-MACHINE.

SPECIFICATION forming part of Letters Patent No. 315,817, dated April 14, 1885.

Application filed February 27, 1885. (No model.)

To all whom it may concern:

Be it known that I, THOMAS MORTON, a citizen of the United States, residing at New York, in the county of New York and State 5 of New York, have invented a new and useful Improvement in Riveting-Machines, of which the following is a specification, reference being had to the accompanying drawings.

My invention relates to an improvement in 10 riveting-machines; and it consists in the peculiar construction and combination of devices, that will be more fully set forth herein-after.

In the accompanying drawings, Figure 1 is 15 a side elevation of a machine embodying my invention. Fig. 2 is a front elevation of the same.

A represents a frame or standard, which extends vertically, is provided at its lower 20 end with a horizontal arm or base, B, at its upper end with a horizontal arm, C, and at a suitable distance above the base with an arm, D. The arms B, C, and D are on the same side and in a vertical line. On the arm B, on 25 its upper side, is located an anvil, E, which is adapted to be removed from the arm and replaced by another, and in the upper side of this anvil, in the center thereof, is made a countersink, e, which corresponds to the size 30 and shape of the rivets that are to be used in the work to be riveted by the machine.

F represents a hammer-shaft that slides vertically in the arms C and D. To this shaft, at a suitable distance from its upper end, is 35 fixed a horizontal disk, G, having ratchet-teeth g on its upper face, and from this disk, surrounding the hammer-shaft, projects the vertical sleeve f. A coiled spring, H, is placed around the upper portion of the shaft F, and 40 bears between the under side of the arm C and the upper side of the sleeve f. The function of the spring is to keep the hammer-shaft normally forced down upon the anvil. In the lower end of the hammer-shaft is socketed a hammer-head, I, in the hammer-face of 45 which, centrally therein, is made a conical countersink, i, that is on a vertical line with the countersink e.

K represents a pawl that is secured to the 50 standard A near the upper end thereof, and,

when the hammer-shaft is raised, engages with one of the ratchet-teeth thereof.

At a suitable distance below the pawl K is a pivoted arm, L, which is connected to the pawl by a spring, M.

N represents the end of a rotating shaft that is actuated by any suitable machinery, (not shown,) and that extends between the standard and the hammer-shaft at a suitable height. This shaft has tappet-pins n, which, as the shaft 60 revolves, strike against the under side of the disk G and raise the hammer-shaft against the tension of the spring H. As the tappet-pins pass beyond the disk the spring causes the hammer-shaft to descend with force upon the 65 end of the rivet-shank.

While the hammer-shaft is being raised, and before it reaches the upward limit of its motion, the pawl engages with one of the teeth of the ratchet-disk, and as the hammer-shaft 70 continues to rise causes the shaft to partially rotate. By thus partially rotating the shaft at each blow I adapt the machine to form symmetrical conical-shaped heads to the rivet-shanks. One of these rivets I show at x before the conical head is formed thereon, and at z when it is finished. The pivoted arm L prevents the pawl from swinging in toward the standard far enough to clear the ratchet-disk. By raising or lowering the free end of the arm 75 L the pawl is caused to engage with the ratchet-disk at a higher or lower point in the elevation of the hammer-shaft, and thus cause the shaft to be rotated to a greater or less extent before delivering each blow, as will be 80 very readily understood.

A riveting-machine thus constructed is cheap and simple, is positive and direct in operation, and is adapted to produce finished work. By 85 removing the anvil and hammer-head and substituting for them others having countersinks of a different shape, differently-formed heads may be formed on the rivet-shanks.

Having thus described my invention, I claim—

1. The combination of the reciprocating hammer-shaft having ratchet-teeth, the pawl for engaging with the ratchet-teeth as the hammer-shaft moves, and the pivoted arm connected to the pawl for limiting the action of 90 100

the pawl, for the purpose set forth, substantially as described.

2. The combination of the standard A, the anvil secured thereto, the vertically-reciprocating hammer-shaft having ratchet-teeth, the pawl pivoted to the standard and engaging with the ratchet-teeth, the pivoted arm, and the spring connecting said arm to the pawl, substantially as described.

In testimony that I claim the foregoing as to my own I have hereto affixed my signature in presence of two witnesses.

THOMAS MORTON.
